US0D1102936S

(12) **United States Design Patent** (10) **Patent No.:** **US D1,102,936 S**
(45) **Date of Patent:** **** Nov. 25, 2025**

(54) **NECKLACE**

(71) Applicant: **CARTIER INTERNATIONAL AG**,
Steinhausen (CH)

(72) Inventor: **Emmanuelle Sallard**, Paris (FR)

(73) Assignee: **CARTIER INTERNATIONAL AG**,
Steinhausen (CH)

(**) Term: **15 Years**

(21) Appl. No.: **29/897,700**

(22) Filed: **Jul. 18, 2023**

(30) **Foreign Application Priority Data**

Mar. 10, 2023 (WO) WIPO129935

(51) **LOC (15) Cl.** **11-01**

(57) **CLAIM**

The ornamental design for a necklace as shown and described.

DESCRIPTION

FIG. 1 is a front, right-side, bottom perspective view of a necklace, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

(Continued)

The broken lines depict parts of the necklace that form no part of the claimed design.

1 Claim, 7 Drawing Sheets
